UNITED STATES PATENT OFFICE.

ROBERT BLADES, OF CHICAGO, ILLINOIS.

MEAT HANGER AND APPARATUS FOR APPLYING THE SAME.

Application filed October 9, 1922. Serial No. 593,482.

To all whom it may concern:

Be it known that I, ROBERT BLADES, a citizen of the United States, and a resident of the city of Chicago, in the county of Cook and State of Illinois, have invented certain new and useful Improvements in a Meat Hanger and Apparatus for Applying the Same; and I do hereby declare that the following is a full, clear, and exact description 10 of the same, reference being had to the accompanying drawings, and to the numerals of reference marked thereon, which form a part of this specification.

This invention relates to a meat hanger 15 and apparatus for applying the same, and particularly to an improved means for engaging a flexible member through a piece of meat or similar material so that the same may be conveniently suspended by said 20 member for curing, smoking, storage and the like.

Heretofore it has been the general custom to thread ordinary twine through the portion of the meat to be suspended, after which 25 the twine was knotted to complete the hanger.

This operation has proven objectionable in that it is time-taking and expensive and in that deterioration of the twine caused an 30 unsanitary condition, and an important object of the present invention consists in the provision of an improved meat hanger which is sanitary, inexpensive and which may be quickly and conveniently engaged through 35 the piece of meat to be suspended and which is firmly retained in position when engaged therethrough.

It is a further important object of this 40 invention to provide a device of the class described having coacting applying means for facilitating the permanent engagement of the hanger with the material or article to be suspended.

Other and further important objects of 45 the present invention will be apparent from the disclosures in the specification and the accompanying drawings.

The invention (in a preferred form) is 50 illustrated in the drawings and hereinafter more fully described.

On the drawings:

Figure 1 is a side elevation of the applying tool for the hanger of this invention.

Figure 2 is a side elevation illustrating 55 the method of applying the hanger with the applying tool.

Figure 3 is an enlarged fragmentary bottom plan view of the applying tool.

Figure 4 is a section on the line 4-4 of 60 Figure 3 with parts in elevation.

Figure 5 is a plan view of a hanger embodying the principles of this invention.

Figure 6 is a section on the line 6-6 of 65 Figure 4.

Figure 7 is a section on the line 7-7 of Figure 4.

Figure 8 is a plan view of a slightly modified form of hanger.

As shown on the drawings:

A preferred form of hanger embodying 70 the principles of this invention is shown in Figure 5 wherein the reference numeral 1 indicates a flexible connecting member which is preferably formed of wire of non-corrosive material or a material provided with 75 a non-corrosive coating, and which has secured to either end a flat metallic plate 2 which is also constructed of non-corrosive material or provided with a non-corrosive coating. 80

Formed at either end of said flat metallic plates 2 on the inner face thereof are integral bosses or extensions 3, while similar extensions or bosses 4 are formed on the same sides of said plates at the points where 85 the flexible member 1 is connected thereto.

In the modified form of hanger which is 90 illustrated in Figure 8, one of the plates 2 is supplanted by a loop 5 which may be formed in the flexible member 1 in any well-known manner.

Embodied in the present invention is a 95 piercing or applying tool which is used in connection with my improved hanger for inserting the hanger through a ham, a slice of bacon or any other mass of organic material which is to be suspended by the hanger. Said piercing tool is provided with a handle 6 which has secured thereon an axial metallic shank 7, and on the outer 100 end of said metallic shank 7 is an enlarged portion 8 which is provided on its lower side with a groove or recess 9, as clearly indicated in Figures 3 and 4. The outer end of said groove or recess 9 terminates in a slot in which is mounted a pointed blade portion 10 which is secured in said slot by

means of rivets 11 and the sharpened portion of which extends rearwardly to points 12 both at the top and bottom of the blade. A 105 rearward extension 13 is formed on the lower part of the blade portion extending

along the bottom of the groove 9 to a cut-out portion 14 which is formed in the member 8 intermediate the ends thereof.

As clearly shown in Figure 4, a depression 15 is formed in the inner face of said extension 13 and said depression 15 is adapted to receive a boss 3 on one end of the plate 2 when the same is inserted in the groove 9, said plate 2 being releasably held 10 in said groove in the position shown in Figure 4 by means of a flat leaf spring 16 which is secured at one end in said groove, as indicated in Figure 4, by means of a rivet 17.

In order to facilitate the removal of 15 pieces of material from the groove 9, an aperture 18 is provided in the outer end of the member 8 extending transversely of said groove and permitting the ready insertion of a tool therethrough to push out 20 waste material.

In applying the improved hanger of this invention the plate 2 on one end of the flexible member 1 is secured in position in the slot 9 in the portion 8 of the piercing tool, 25 in the manner indicated in Figures 2 and 4, the spring 16 serving to hold said plate in proper position in said slot 9. The tool is then engaged through the article to be suspended as, for example, a ham 19, and 30 as the tool is forced through the article the flexible member 1 is of course also drawn therethrough until the plate 2 or the loop 5 on the other end of said member contacts the rear side of the ham or other article 35 in the manner indicated in dotted lines in Figure 2, at which time the tension on the flexible member 1 is sufficient to pull the forward plate 2 from the slot 9. The piercing tool may then be withdrawn, leaving the 40 hanger in position for use, whereupon either plate 2 may be used for engagement with a hook or other suitable hanging means, or, if desired, in the form of hanger shown in Figure 8 the plate 2 may be drawn through 45 the loop 5 prior to the time the same is hung on the hook.

It will be apparent that this invention provides not only an inexpensive and sanitary hanger but also provides an apparatus 50 and method of quickly and conveniently applying the same, wherein the necessity of knotting is eliminated.

I am aware that various details of con-

struction and methods of application may be considerably changed without departing 55 from the spirit of this invention, and I therefore do not purpose limiting the patent granted hereon otherwise than necessitated by the prior art.

I claim as my invention:

1. The combination with a pointed member, of a recess therein, a spring mounted in the recess, a member adapted to be releasably maintained in the recess by the spring, flexible means connected to said last mentioned member, and a similar member connected to said flexible means and separated from said member.

2. The combination with a pointed member, of a recess therein, resilient means mounted in the recess, a member adapted to be releasably maintained in the recess by said resilient means, flexible means connected to said last mentioned member, and laterally extending means connected to said flexible means and separated from said last mentioned member.

3. The combination with a pointed member, of a recess therein, a flat leaf spring mounted in the recess, a member adapted to be releasably maintained in the recess by said spring, flexible means connected to said last mentioned member, and a similar member connected to said flexible means and separated from said member.

4. The combination with a pointed member, of a recess therein, a flat plate releasably mounted in the recess, flexible means connected to said flat plate, and a similar flat plate connected to said flexible means and separated from the first mentioned plate.

5. The combination with a piercing member having a recess therein, of rigid means releasably mounted in the recess, flexible means connected to said rigid means, and additional rigid means connected to the flexible means and separated from the first mentioned rigid means.

In testimony whereof I have hereunto 100 subscribed my name in the presence of two subscribing witnesses.

ROBERT BLADES.
